UNITED STATES PATENT OFFICE.

FRANK TAYLOR CABLE, OF QUINCY, MASSACHUSETTS.

AUXILIARY VALVE FOR AUTOMOBILE-ENGINES.

No. 848,722.

Specification of Letters Patent.

Patented April 2, 1907.

Application filed October 18, 1906. Serial No. 339,471.

To all whom it may concern:

Be it known that I, FRANK TAYLOR CABLE, a citizen of the United States, residing in Quincy, county of Norfolk, and State of Massachusetts, have invented a new and Improved Auxiliary Valve for Automobile-Engines, of which the following is a specification.

My invention relates to automobile-engines of the class known as "explosion-engines," in which the charge of fuel in the cylinder is exploded by electrical ignition devices.

The object of my invention is to provide means for increasing the power of such engines, prolonging the life of the ignition-battery, for saving wear on the brakes, and for producing an additional or auxiliary brake.

According to my invention, I provide a combined auxiliary valve and circuit making and breaking device so constructed that in breaking the ignition-circuit the valve is opened to admit air to the fuel-induction pipe between the engine and the carbureter or source of supply, which will have the effect of breaking the suction of fuel and supplying only air to the cylinder, which serves the double purpose of cooling the cylinder and when compressed acts as a powerful brake. This compressed-air brake may be utilized while the automobile is coasting or running down hill.

In the accompanying drawings, Figure 1 is a diagram showing how my improvements may be applied to a gasolene-engine. Fig. 2 shows a vertical section of my improved auxiliary valve on the line 2 2 of Fig. 3. Fig. 3 shows a vertical longitudinal section of the valve and the device for making and breaking the ignition-circuit. Fig. 4 shows an end elevation of the same.

In Fig. 1, A indicates the cylinder of the engine; B, its piston; C, the piston-rod, and D the crank-shaft with which it is connected. E indicates a carbureter, to which fuel is supplied by the pipe e. The fuel passes from the carbureter through an induction-pipe F to an admission-valve G, which is shown as a spring-controlled check-valve automatically opening inward on the outstroke of the piston; but a positively or mechanically operated valve may be substituted. H indicates an exhaust-valve, which is shown as normally held closed by a spring h, and this valve is preferably opened by connections with the crank-shaft or some other suitable part of the mechanism at each stroke or each

alternate stroke of the engine. The igniting devices I are connected with the secondary of the induction-coil J by the circuit-wires x. The primary of the induction-coil is connected with the battery K by the wire k. The other pole of the battery is connected to a contact device L, with which a contact device I on the crank-shaft of the engine engages at each revolution. The other end of the primary of the induction-coil is connected by a wire n with a binding-post M on my improved valve N, and when this valve is closed the circuit extends from the binding-post M to a contact-plate n, thence by a spring V to the valve-stem R', thence to the metal shell of the plug; and thence the circuit is through the metallic pipes, &c., of the engine. Ordinarily the ignition-circuit is closed at the valve N and is made and broken at each revolution of the engine at the contacts L l, and ordinarily fuel is drawn into the cylinder past the admission-valve G at each stroke of the engine and is expelled through the exhaust H after each explosion in the usual manner; but I employ the valve N for the purpose of increasing the power of the engine by admitting regulated quantities of air to the fuel between the carbureter and the engine-cylinder, and by means of this valve, when the automobile is coasting or running down a steep grade, air may be admitted in such quantities as to practically cut off the flow of fuel from the carbureter to the engine. The air thus received in the cylinder serves to cool it, and by being compressed will act as a powerful brake, thus dispensing to a large extent with the use of the mechanical brakes, and thus increasing their life.

It will be understood, of course, that the exhaust-valve H is opened at each stroke or each alternate stroke of the engine; but, nevertheless, there will be a compression of air in the cylinder which will act as a brake, and when the automobile is running very rapidly, as when coasting down a steep grade, the wheels will be held with a very powerful braking-action.

In going down a steep grade the engine should be thrown into the intermediate low-gear position. In the low-gear position the compression would practically stop the heaviest car on account of the high speed at which the engine would be running and the slow speed at which the car would be moving. In going down a hill of medium grade sufficient

braking power would be obtained with the engine on high gear.

The details of the valve may be varied, but preferably the combined valve and circuit-breaker are constructed as shown in the drawings. The shell P of the valve has a conical bore or valve-seat receiving a conical valve R, which is operated by a handle S. The valve R has a passage r, communicating with the port r' in the valve-casing opening to the atmosphere and with the port r^2 in the casing connected with a pipe T, which communicates at t with the induction-pipe F between the engine-cylinder and the carbureter. By means of the lever S the valve may be turned to entirely cut off communication between the port r' and the induction-pipe, or it may be so turned as to admit any desired quantity of air to increase the efficiency of the explosive charge, or it may be thrown wide open, so as to permit the free access of atmospheric air to enter; and, as at this time the throttle-valve of the engine would be closed, practically no fuel would enter the engine-cylinder with the air thus admitted. The lever S is also made to open and close the ignition-circuit. The contact n , before described, is mounted on a disk U of insulating material, which is secured to the valve-casing, as by a screw u . The stem R' of the valve carries spring contact-fingers V, which are electrically connected with each other and are held in place by a nut W on the valve-stem. The upper finger V makes contact with the plate n . The lower finger merely slides on the face of the disk U and across the head of the screw u , but is not in the electric circuit. When the lever S is in the position shown in Fig. 3, no air enters the induction-pipe through the valve N, and the ignition-circuit is closed. The lever may be turned to a limited extent, if desired, without break-

ing the circuit between the upper finger V and the plate n , so as to admit some air to the fuel-induction pipe; but when the lever is thrown to the extent shown by dotted lines in Fig. 4 the ignition-circuit is broken, and air is freely admitted from the atmosphere to the induction-pipe.

I claim as my invention—

1. The combination with the induction-pipe of an explosion-engine, of an auxiliary valve for admitting air to the pipe, an ignition-circuit and contact making and breaking devices operated simultaneously with said auxiliary valve.

2. The combination with an explosion-engine of ignition devices, a carbureter, an induction-pipe leading from the carbureter to the engine-cylinder, an auxiliary valve for admitting atmospheric air to the induction-pipe interposed between the carbureter and the engine-cylinder and circuit making and breaking devices in the ignition-circuit operated simultaneously with said valve.

3. An auxiliary valve for automobile-engines comprising a valve-casing having a port opening to the atmosphere and another port connected with the induction-pipe of the engine, a valve for opening and closing communication between said ports and circuit making and breaking devices carried by said valve whereby the ignition-circuit of the engine may be opened when the valve is open to establish communication between said ports and will be closed when the valve is closed.

In testimony whereof I have hereunto subscribed my name.

FRANK TAYLOR CABLE.
